UNITED STATES PATENT OFFICE.

BENJAMIN GOLDENBERG, OF NEW YORK, N. Y., ASSIGNOR TO E. I. HORSMAN & AETNA
DOLL CO., INC., OF NEW YORK, N. Y., A CORPORATION OF NEW YORK.

DESIGN FOR A DOLL.

55,561.

Specification for Design. Patented June 29, 1920.

Application filed January 21, 1920. Serial No. 353,091. Term of patent 7 years.

To all whom it may concern:

Be it known that I, BENJAMIN GOLDENBERG, a citizen of the United States, residing at New York city, in the county and State of New York, have invented a new, original, and ornamental Design for a Doll, of which the following is a specification, reference being had to the accompanying drawing, forming part hereof.

The figure shown is a perspective view of a doll, showing my new design.

I claim:

The ornamental design for a doll, as shown.

BENJAMIN GOLDENBERG.
